United States Patent

Des. 241,590
Patented Sept. 28, 1976

241,590

SEAT

Burton H. Kaplan, Potomac, Md., assignor to
Rowe Furniture Corporation

Filed May 13, 1975, Ser. No. 577,080

Term of patent 14 years

Int. Cl. D6—01

U.S. Cl. D6—63

FIG. 1

FIG. 2

FIG. 3

FIG. 4

FIG. 1 is a front perspective view of a seat in the form of a davenport;

FIG. 2 is a side elevation of a seat illustrated in FIG. 1;

FIG. 3 is a rear elevation of a seat illustrated in FIG. 1; and

FIG. 4 is a front perspective view of a seat illustrated in FIG. 1, shown in the form of a love seat.

The side of the seat not shown in FIG. 2 is a mirror image of the side shown.

I claim:

The ornamental design for a seat, substantially as shown and described.
